1,920,552

DETACHABLE SAFETY LADDER STEP

Charles M. Dollerhide, Davenport, Iowa

Application December 26, 1929. Serial No. 416,547

3 Claims. (Cl. 304—34)

One object of this ladder step is to relieve the strain due to limited bearing of a ladder rung under the feet of a person standing upon a ladder for an appreciable length of time.

5 Another object is to distribute the weight of the operator upon the elements of two ladder rungs most advantageously placed to support such weight, namely, near the side pieces of the ladder thus reinforcing the ladder itself.

10 To accomplish these objects, use is made of a metal plate having the ends and farther edge turned downward to form stiffening flanges, the nearer edge being turned downward to hook over the ladder rung. The nearer ends of the end flanges together with the hook element of the nearer edge effectually prevent slippage of the step in the horizontal plane. The farther corners of the plate are suspended from the next higher rung of the ladder by rods of metal engaged in 15 holes pierced in the end flanges of the plate. The lower ends of the rods are formed in U-shape angularly disposed relatively to the plane of hooks at the upper ends of the rods.

These practical features of my invention are 20 shown in the accompanying drawings wherein Fig. 1 is a view of the detachable safety ladder step as usually applied to a ladder. Fig. 2 is a view showing the step lifted as in movement from one rung of the ladder to another, and with the 25 hooked upper ends of the rods conveniently gathered in one hand. Fig. 3 is a view of the bottom of the plate with the rods compactly folded for storage or transport.

The numeral 1 indicates the plate; 2 is a depending end flange of the plate; 3 are rods with hooked upper ends 4 and U-shaped lower ends 5. 30 6 shows a secondary perforation in the end flange of the plate to admit the short leg of the rod hook in folded position. 7 is a button or enlargement of the lower end of the rod to prevent that end from pulling through the flange of the plate. The formation of the lower ends (5) of the rods (3) is so proportioned that as the step is 35 lifted as shown in Fig. 2, the hooks (4) naturally assume the positions necessary to engage over a

rung of the ladder thus greatly facilitating the operation of adjusting the step from one rung of the ladder to another. It is not essential to the invention that the extremity (7) be formed as an enlargement of the rod and it will be understood that the end of the rod may be turned back upon itself or any other convenient method used to accomplish the object of enlargement.

Having now described the construction of my invention, I claim, —

60 1. In a detachable ladder step, a metal plate with depending end flanges each provided with a pair of perforations, rods having upper hook elements and having lower ends formed in substantially U-shape angularly disposed relatively to the plane of the upper hook elements, said rods assembled in one of the perforations of each end flange of the plate and the prongs of said hook elements being adapted to engage in the other perforation of each of said flanges when said step is in a folded position.

65 2. In a detachable ladder step, a metal plate formed to engage over one rung of a ladder, a perforated flange depending from each end of said plate, rods suspending the farther corners of the plate and having hooks at one end adapted to engage a higher rung, the other ends of the said rods formed in U-shape angularly disposed with reference to the plane of the hooks of said rods, and engaged in the perforations in the end flanges of the plate, and means for preventing the passage of the lower extremities of the rods through the perforations of the flanges.

70 3. In a detachable ladder step, a metal plate with depending end flanges each provided with a pair of perforations, rods having upper hook elements and having lower ends formed in substantially U-shape angularly disposed relatively to the plane of the upper hook elements, said rods assembled in one of the perforations of each end flange of the plate and the prongs of said hook elements being adapted to engage in the other perforation of each of said flanges when said step is in a folded position.
